(21) Appl. No.: **29/208,483**

CLAIM

(22) Filed: **Jun. 29, 2004**

The ornamental design for a monkey-style air freshener device, as shown.

(51) LOC (6) Cl. **23-04**

DESCRIPTION

(52) U.S. Cl. **D23/367**

FIG. 1 is perspective view of a monkey-style air freshener device embodying the present invention;

(58) Field of Search D23/356-369;
392/390, 392, 394; 239/135, 136, 58; 261/DIG. 17,
DIG. 65; D21/576, 587, 596

FIG. 2 is a front view of the air freshener device;

(56) **References Cited**

FIG. 3 is a rear view of the air freshener device;

U.S. PATENT DOCUMENTS

FIG. 4 is a left side view of the air freshener device;

D391,456 S * 3/1998 Henry et al. D7/684

FIG. 5 is a right side view of the air freshener device;

D401,317 S * 11/1998 Gillies D23/356

FIG. 6 is a top view of the air freshener device; and,

D433,862 S * 11/2000 Rosenstadt et al. D6/598

FIG. 7 is a bottom view of the air freshener device.
